DESIGN FOR A DISPLAY STAND FOR TOILET POWDERS

Arthur Botham, New York, N. Y., assignor to Coty, Inc., Wilmington, Del., a corporation of Delaware

Application September 25, 1935, Serial No. 58,699

Term of patent 7 years

To all whom it may concern:

Be it known that I, Arthur Botham, a citizen of the United States, residing at 14 East 75th Street, in the city of New York, county of New York, and State of New York, have invented a new, original, and ornamental Design for a Display Stand for Toilet Powders, of which the following is a specification, reference being had to the accompanying drawing, forming a part thereof.

Fig. 1 is a front elevational view of the display stand for toilet powders, showing my design;
Fig. 2 is a side elevational view; and
Fig. 3 is a top plan view thereof.

I claim:—

The ornamental design for a display stand for toilet powders, substantially as shown.

ARTHUR BOTHAM.
